Primary Examiner — Janice Hallmark(74) *Attorney, Agent, or Firm* — McGarry Bair PC(57) **CLAIM**

The ornamental design for a ceiling fan light kit as shown and described.

DESCRIPTION

FIG. 1 is a bottom perspective view of a ceiling fan light kit, shown in the environment of a ceiling fan, showing our new design;

FIG. 2 is a top perspective view of the ceiling fan light kit of FIG. 1, without the ceiling fan environment;

FIG. 3 is a bottom view thereof;

FIG. 4 is a top view thereof; and,

FIG. 5 illustrates a right side view thereof, with the left, front, and rear side views all being the same.

Broken lines illustrate portions of the ceiling fan light kit that form no part of the claimed design. Additional broken lines in FIG. 1 showing a ceiling fan illustrate environment and form no part of the claimed design.
